UNITED STATES PATENT OFFICE.

LEONA A. STOUGH, OF DURANGO, COLORADO.

PENCIL-SHARPENER.

SPECIFICATION forming part of Letters Patent No. 593,912, dated November 16, 1897.

Application filed January 13, 1897. Serial No. 619,088. (No model.)

To all whom it may concern:

Be it known that I, LEONA A. STOUGH, a citizen of the United States, residing at Durango, in the county of La Plata and State of Colorado, have invented a new and useful Pencil-Sharpener, of which the following is a specification.

This invention relates to improvements in pencil-sharpeners.

10 The object of the present invention is to improve the construction of pencil-sharpeners and to provide a simple, inexpensive, and efficient device capable of rapidly sharpening a pencil and of collecting the shavings and other waste to prevent the same from accumulating upon a desk, table, or other support.

15 A further object of the invention is to provide a pencil-sharpener which will be capable of supporting a pencil in proper position for sharpening it, and thereby prevent the point from being accidentally broken while it is being sharpened.

20 The invention consists in the construction and novel combination and arrangement of parts, hereinafter fully described, illustrated in the accompanying drawings, and pointed out in the claims hereto appended.

25 In the drawings, Figure 1 is a side elevation of a pencil-sharpener constructed in accordance with this invention. Fig. 2 is a vertical sectional view of the same. Fig. 3 is a horizontal sectional view on line $x-x$ of Fig. 1.

30 Like numerals of reference designate corresponding parts in the several figures of the drawings.

35 1 designates a base from which rises a vertical spindle 2, preferably formed integral with the same and receiving a tubular shank 3 of a rotary pencil-holder 4, which is provided with a head 5. The base may be provided with perforations for the reception of suitable fastening devices for securing the pencil-holder to a desk, table, or other support. The spindle 2 is provided near its lower end with an annular shoulder, and it has a conical seat 6 at its upper end to receive a cone-bearing 40 7 at the top of the tubular shank 3 of the rotary pencil-holder.

45 The head of the rotary pencil-holder is provided with a vertical pencil-receiving opening or cavity 8, consisting of a cylindrical upper

portion and a conical lower portion. The cylindrical upper portion of the pencil-receiving opening or cavity 8 conforms to the configuration of and is adapted to steady a pencil to prevent the point from being accidentally broken during the sharpening operation. The rotary pencil-holder is provided in its head with a slanting or inclined slot or opening 8^a, in which is detachably mounted a knife-blade 9, and the inclined slot or opening communicates with the conical portion of the pencil-receiving opening to enable the blade to engage a pencil. The pencil is held stationary while the holder is rotated by gearing herein-after described, and the slanting blade, which is provided with an inner cutting edge, gives the pencil the proper taper.

50 The blade 9 is provided with horizontal slots 10, and is secured to the head of the pencil-holder by means of screws 11 passing through the said slots and engaging threaded sockets of the head. It is adjusted by means of set-screws 12, disposed horizontally in threaded openings of lugs or projections 13 and arranged to engage the outer edge of the blade, whereby the latter is forced inward.

55 The pencil-sharpener is rotated by means of beveled gear-wheels 14 and 15, mounted, respectively, on the lower end of the tubular shank and the inner end of a horizontal shaft 16. The shaft 16 is journaled in suitable bearings of a vertical support 17, and is provided at its outer end with a crank-handle, by means of which it is rotated. Oil-holes are provided 60 at the top and bottom of the tubular shank and near the upper end of the support 17, so that the parts can be thoroughly lubricated. The shavings and other waste fall into a receptacle 18, located directly beneath the head of the rotary pencil-holder and mounted on the tubular shank thereof. The receptacle, which tapers toward its base and which is designed to be readily removable, is of a sufficient diameter at its top to receive the shavings as they fall from the opening or slot 8^a of the pencil-holder and effectually prevents such waste from falling upon a table, desk, or other support. The receptacle rotates rapidly during the sharpening operation, and in 65 order to prevent the shavings from being thrown out of it by centrifugal force it is pro-

vided at its upper edge with an inwardly-extending inclined rim 18^a. Any suitable construction may be provided for removably mounting the receptacle on the pencil-holder. 5 It will be seen that the pencil-sharpener is exceedingly simple and inexpensive in construction, that it is positive and reliable in operation, and that it is capable of rapidly sharpening a pencil and collecting the waste 10 to prevent the latter from accumulating on a table, desk, or other support. It will also be apparent that it is adapted to steady and guide a pencil to prevent the point from being accidentally broken during the sharpening operation and that the knife-blade is capable of 15 ready adjustment to produce the proper cut and may be readily removed when it is necessary to sharpen it.

Changes in the form, proportion, and minor 20 details of construction may be resorted to without departing from the spirit or sacrificing any of the advantages of this invention.

What I claim is—

1. In a pencil-sharpener, the combination 25 of a base, a vertical spindle mounted thereon, a rotary pencil-holder disposed vertically and composed of an upper pencil-receiving head and a lower tubular shank arranged on the said spindle, a support rising from the base, 30 a horizontal shaft journaled on the support,

and gearing connecting the shaft with the tubular shank, substantially as described.

2. In a pencil-sharpener, the combination of a base, a vertical spindle rising from the base, a rotary pencil-holder having a tubular 35 shank arranged on the spindle, a blade carried by the rotary pencil-holder and arranged to engage a pencil, a receptacle mounted on and carried by the tubular shank and arranged beneath and extending around the 40 blade in position to receive the shavings, and gearing for rotating the pencil-holder, substantially as described.

3. In a pencil-sharpener, the combination of a rotary pencil-holder having a pencil-receiving opening, a blade, a receptacle mounted on the pencil-holder and located below the blade, said receptacle being provided at its upper edge with an inwardly-extending rim adapted to prevent the shavings from being 45 thrown out of the receptacle by centrifugal force, and means for rotating the pencil-holder, substantially as described.

In testimony that I claim the foregoing as my own I have hereto affixed my signature in 55 the presence of two witnesses.

LEONA A. STOUGH.
